UNITED STATES PATENT OFFICE.

FREDERICK KAUPMANN, OF BROOKLYN, NEW YORK, ASSIGNOR TO JOSEPH FAHYS & COMPANY, OF NEW YORK, N. Y., A CORPORATION OF NEW YORK.

DESIGN FOR A SPOON, FORK, OR SIMILAR ARTICLE.

52,168.

Specification for Design.

Patented July 9, 1918.

Application filed April 27, 1918. Serial No. 231,259. Term of patent 7 years.

To all whom it may concern:

Be it known that I, FREDERICK KAUPMANN, a citizen of the United States, residing at Brooklyn, in the county of Kings, in the State of New York, have invented a new, original, and ornamental Design for Spoons, Forks, or Similar Articles, of which the following is a specification, reference being had to the accompanying drawing, forming part thereof.

In said drawing:

Figure 1 is a plan view of my design for spoons, forks or similar article;

Fig. 2 is a cross-sectional view of the end portion of the handle.

I claim:

The ornamental design for a spoon, fork or similar article, as shown.

FREDERICK KAUPMANN.
